DESIGN FOR A LIGHTING-FIXTURE BRACE

Application filed April 28, 1930. Serial No. 35,417. Term of patent 3½ years.

To all whom it may concern:

Be it known that I, ARMIN SCHELER, a citizen of the Republic of Germany, and a resident of the city, county, and State of New York, have invented a new, original, and ornamental Design for Lighting-Fixture Braces, of which the following is a specification, reference being had to the accompanying drawing, forming a part hereof.

In the drawing:

Figure 1 is a front elevational view of the lighting fixture brace; and

Figure 2 is an edge view of the same.

I claim:

The ornamental design for a lighting fixture brace substantially as shown.

ARMIN SCHELER.
